UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

THREAD-HOLDER.

1,269,082.

Specification of Letters Patent. Patented June 11, 1918.

Application filed June 7, 1916. Serial No. 102,354.

To all whom it may concern:

Be it known that I, GEORGE S. HILL, a citizen of the United States, residing at Strafford, in the county of Strafford and State of New Hampshire, have invented certain new and useful Improvements in Thread-Holders; and I do hereby declare the following to be a full, clear, and exact description of the invention, such as will enable others skilled in the art to which it appertains to make and use the same.

This invention relates to that class of sewing machines in which the stitch forming mechanism is rotated during the sewing operation, as, for example, in certain types of buttonhole machines, and more particularly to thread holders for the same. The invention is intended primarily as an improvement on the buttonhole sewing machine shown and described in Patent No. 1,063,880, June 3, 1913, although it is not confined in its application to this machine, but may be embodied with advantage in other machines.

In the machine of the above patent, the stitch forming mechanism is turned, rotation after rotation, in the same direction in sewing about successive buttonholes, and in order to prevent the twisting together of the stay and under threads, they are led to the turret on which the under thread mechanism is mounted through thread guides which are rotated in unison with the turret and in the opposite direction. The supply of stay thread is carried by a rotating cop holder rotated in unison with the guides and mounted upon a hollow spindle through which not only the stay thread but also the under thread passes, a suitable thread guide being carried by the cop holder for conducting the under thread from another supply into the hollow spindle.

The object of the present invention is to provide a novel and improved rotating thread holder which shall be adapted to hold and deliver thread from a supply either in the form of a cop or in the form of a ball. With this end in view, the present invention comprises the features of construction and combinations of parts hereinafter described, and more particularly defined in the claims.

In the accompanying drawings, which

illustrate what is now considered to be the preferred form of the present invention, Figure 1 is a side view showing a button-hole sewing machine with the improved thread holder in section; Fig. 2 is a vertical section on a larger scale of the thread holder by itself, taken on the line 2-2 of Fig. 3 looking in the direction of the arrow; and Fig. 3 is a top plan view of the holder shown in Fig. 2 with the thread cop removed.

In the buttonhole sewing machine illustrated in Fig. 1, the under sewing thread *t* and the stay thread or cord *s* are led to the revolving turret 1 which carries the lower sewing mechanism through a series of rotating guides 2, 3, 4, 5, from the source of supply. The supply of the stay thread or cord, which is shown in Fig. 1 in the form of a ball 6 and in Fig. 2 in the form of a cop 7, is supported in a thread holder mounted to rotate about a hollow spindle 8 through which both the sewing thread *t* and stay cord *s* are led. The spindle 8 is mounted to turn in a suitable bearing in the frame of the machine and carries at its lower end a sprocket wheel 9 which is driven through suitable connections to impart rotation to the thread holder for each rotation of the turret and in the opposite direction.

The thread holder proper comprises a bottom 10 provided with a central aperture 85 through which projects the upper end of the hollow spindle 8 to form a thread passage 11. Integrally formed with, and extending downwardly from, the bottom 10 is the boss or hub 12, split on one side and provided with the clamping screw 13 for clamping the hub tightly upon the hollow spindle 8. The bottom of the holder, which is provided with a plurality of holes 14 to reduce the weight, is formed with an upwardly extending peripheral rim or flange 15 to which is fixed the cylindrical wall 16, thus forming a cup-shaped receptacle adapted to hold either a cop or ball of thread as may be desired.

Extending down the outside of the side wall 16 at diametrically opposite points and beneath the bottom 10 and connecting with the interior of the hollow spindle 8 are the side thread guides or tubes 17 and 18, the lower portions of which are formed of the

bent tubes 19 and 20 respectively, the bottom ends of which project into apertures formed on opposite sides of the hub 12, while the top ends enter the sleeves 21 secured to the wall of the holder by the clamps or brackets 22 riveted thereto. The upper portion of the thread guide 17 which conducts the sewing thread *t* from some suitable source of supply (not shown) into the 10 hollow spindle 8, consists of a curved or bent tube 23 which overhangs the thread holder or receptacle being pivotally mounted within the sleeve 21 with its upper end substantially in line with the axis of rotation of the thread holder. This construction permits the overhanging end of the sewing thread guide to be swung to one side so that a new cop or ball of stay cord may be placed in the holder.

20 The upper portion of the stay thread guide 18 is formed of a short section of tube 24 pivoted in the sleeve 21 and having the overhanging arm 25. At the extremity of this arm is located the thread guiding aperture 26, substantially in line with the axis of the holder, through which the stay cord passes when the supply is in the form of a ball, as shown in Fig. 1. Other thread apertures 27 and 28 are provided in the arm 25 through which the thread may be led to increase the drag or tension of the thread. By swinging the overhanging arm 25 to one side a new supply of thread may be inserted in the receptacle.

35 A felt disk 28 is placed between the bottom of the supply receptacle and the ball or cop of thread contained therein.

When it is desired to use a cop of stay thread instead of a ball, the overhanging arm 25 and side guide 18 are not used, but the thread from the cop is led down through the center of the cop and through the thread passage 11 in the bottom of the holder and thence through the hollow 45 spindle 8. The devices for so guiding the thread comprise a tube 29 having secured in its lower end and projecting therefrom a short supporting sleeve or tube 30 adapted to fit snugly within the upper end of the 50 hollow spindle 8 so that the tube 29 will be held frictionally in position but may readily be removed when it is desired to use a ball of stay cord. Mounted in the upper end of the tube 29 is the thread guide 31 having a 55 central thread passage 32 and tension spring 33 for imparting the proper amount of drag or tension to the cord.

60 By the construction above described either a ball or a cop of stay thread may be employed, it being only necessary to remove or replace the central thread guiding device in changing from a ball to a cop and vice versa.

While the present invention has been 65 shown and described in connection with a

particular type of button hole sewing machine, it is not necessarily limited in its application to such a machine, but is capable of use in other machines. Nor is the present invention to be limited to the specific construction and arrangement of parts shown and described, but it may be embodied in many different forms.

Having thus explained the nature and object of the invention, and specifically described one form in which it may be embodied, what is claimed is:

1. A rotary thread holder for sewing machines, having, in combination, means for holding a cop or a ball of thread at the 75 option of the operator and provided with a thread passage at its bottom, a guide for guiding the thread from the supply when in the form of a cop through the center of the cop and through the thread passage, a side 80 guide for guiding the thread from the thread supply when in the form of a ball along the side thereof, and mechanism for rotating said means.

2. A rotary thread holder for sewing machines, having, in combination, means for holding the supply of thread and provided with a thread passage at its bottom, a removable hollow thread guide for guiding the thread from the supply when in the 90 form of a cop through the center of the cop and through the thread passage, a side 95 thread guide for guiding the thread from the thread supply when in the form of a ball along the side thereof, and mechanism for rotating said means.

3. A rotary thread holder for sewing machines, having, in combination, a hollow 100 spindle, a receptacle for the thread supply mounted to turn about the axis of the hollow 105 spindle and provided with a thread passage in its bottom, a removable tube frictionally supported in line with the thread passage for guiding the thread from the thread supply contained in the receptacle when in the 110 form of a cop through the center thereof and through the thread passage and hollow spindle, and a guide tube on the outside of the receptacle and communicating with the hollow spindle and provided with a pivoted 115 overhanging member for guiding the thread from the thread supply when in the form of a ball along the side of the receptacle and through the spindle, means for guiding thread from another source of supply 120 through the hollow spindle, and mechanism for rotating the receptacle and guides about the axis of the hollow spindle.

4. A rotary thread holder for sewing machines, having in combination, a hollow 125 spindle, means for holding a supply of thread and mounted to turn about the axis of the hollow spindle, a thread guide for leading the thread from said thread supply along the side of the same and through the 130

hollow spindle, an auxiliary thread guide for leading thread from another supply through the hollow spindle, and mechanism for rotating the thread holding means and 5 the thread guides.

5. A rotary thread holder for sewing machines, having, in combination, a hollow spindle, a receptacle for the thread supply mounted to turn about the axis of the hollow 10 spindle, a pair of thread guides each com-

prising a bent tube extending down the side of the receptacle and beneath the bottom thereof and communicating with the hollow spindle, and an overhanging upper portion pivoted upon the lower portion, the free 15 ends of such portions being substantially in line with the axis of rotation of the thread holder, and means for rotating the holder.

GEORGE S. HILL.
